(57) CLAIM

I claim the ornamental design for a fanciful fabric panel, as shown and described.

DESCRIPTION

FIG. 1 is a front perspective view of a fanciful fabric panel showing inventor's new design;

FIG. 2 is a front elevational view thereof;

FIG. 3 is a right side elevational view thereof, the left side being a mirror image thereof;

FIG. 4 is a top plan view thereof;

FIG. 5 is a bottom plan view thereof; and,

FIG. 6 is a rear elevational view thereof.

The broken line showing of the fanciful fabric panel in FIGS. 1-6 is included for the purpose of illustrating environmental matter and forms no part of the claimed design.
